UNITED STATES PATENT OFFICE.

JOZSEF KASSA, OF SANDCOULEE, MONTANA.

LIFE-BOAT.

1,105,909.

Specification of Letters Patent.

Patented Aug. 4, 1914.

Application filed May 15, 1914. Serial No. 838,724.

To all whom it may concern:

Be it known that I, JOZSEF KASSA, a subject of the King of Hungary, residing at Sandcoulee, in the county of Cascade and 5 State of Montana, have invented certain new and useful Improvements in Life-Boats, of which the following is a specification.

This invention relates to certain new and useful improvements in life boats.

10 The primary object of this invention is the provision of shiftable keel positioned ballast members upon the hull of a life boat and adapted for imparting stability thereto.

A further object is to provide a life boat 15 with oppositely-positioned longitudinal floats exteriorly of the hull and supported by brackets terminating in keel portions for pivotally-mounting shiftable ballast disks.

A still further object is to provide a 20 spring-motor operable life boat having a serviceable steering device and with opposite exterior longitudinal floats and a plurality of ballast disks pivoted beneath the keel portion of the boat and adapted when 25 released to automatically assume an operative lowermost position spring locked in place.

With these general objects in view and others that will appear as the nature of the invention is better understood, the same consists in the novel combination and arrangement of parts hereinafter fully described, 30 illustrated in the accompanying drawings, and pointed out in the appended claims.

In the drawings forming a part of this 35 application and wherein similar reference numerals designate corresponding parts throughout the several views:—Figure 1 is a side elevation of a life boat provided with the present invention and partially broken 40 away with the ballast device shown in dotted lines in its inoperative position. Fig. 2 is a rear elevation thereof. Fig. 3 is a side view of one of the ballast members with the hinge joint partially broken away. Fig. 4 is a transverse sectional view upon an enlarged scale taken on line IV—IV of Fig. 3. Fig. 5 is an enlarged perspective view of the 45 lower end portions of the clamping supporting strips forming the hinge joint for a ballast last member. Fig. 6 is a top plan view of one of the ballast members in its inoperative position partially broken away and with the supporting strips in section.

Referring more in detail to the drawings, 50 the life boat herein illustrated as provided with the present invention consists of the hull 10 having a propeller 11 operated by a

spring motor 12 within the hull and adapted to be steered by means of a rudder 13 controlled by the steering wheel 14 within the 60 pilot house 15 forwardly positioned upon the deck 16 of the boat. The boat is also provided with oppositely-hinged skylight frames 17 which may be either provided with glass panels or with ventilating screens 65 18 formed of such material as fabric. The said frames 17 are adapted for swinging on the hinges 19 by which they are connected to the deck and are locked closed by means of turn buttons 20.

A trap door 21 is positioned adjacent the bow of the boat and through the deck thereof forwardly of the pilot house 15 while a similar door 22 is pivoted to the deck rearwardly of the skylight frames 17, both of 75 said doors 21 and 22 being normally retained closed by means of engaging springs 23 and 24 respectively.

Clamping supporting strips 25 are oppositely positioned exteriorly of the hull 10 80 and substantially surrounding the same and provided at opposite points slightly beneath the gunwales of the hull with circular brackets 26 adapted for mounting hollow tubular buoys or floats 27 which extend 85 therethrough and are thus positioned longitudinally upon opposite sides of the hull and in the same horizontal plane. The clamping strips 25 being arranged in pairs and the pairs thereof being spaced apart, 90 are provided with downwardly-extended end portions 27 beneath the keel portion of the hull and each pair of strips is provided with a spacing block 28 rigidly secured between 95 said lower ends and in engagement with the bottom of the hull.

Ballast disks 29 are provided each having a handle 30 which is pivoted between the ends of the clamp portions 27 by means of hinge pins 31. The said clamp portions 27 100 are provided with inwardly-struck stop lugs 32 and with inwardly-struck spring lugs 33 adapted to receive the upper reduced extensions 34 of the disk handles 30, it being noted that in the swinging movement of 105 the disks and handles from the inoperative to the operative position or in other words, from the horizontal to the vertical position, the said extension 34 is first resiliently-received between the spring lugs 33 and passing the same seats therebehind and between 110 and in abutting engagement with the stop lugs 32 as best illustrated in Fig. 4. A connecting link 35 is pivotally-connected by

pins 36 to the centers of the ballast disks 29 and which construction insures a simultaneous operation of the disks. The rear disk 29 is connected by means of a chain 37 secured at a point 38 in the periphery thereof opposite to the handle 30 with a ring 39 mounted upon the stern 40 of the boat and in close proximity to the door 22 and whereby an occupant of the boat may raise the door 22 and by pulling upwardly upon the chain 37, move the ballast disks 29 upon their pivot pins 31 and disengaging the extensions 34 from the spring lugs 33, and thus elevate the two disks to their inoperative positions as illustrated in dotted lines in Fig. 1. The forward one of the ballast disks 29 is similarly-connected by means of a chain 37' to a forwardly-positioned hook 39' upon the deck 16 at a point in close proximity to the forward door 21. When the disks are in their inoperative position, it will be seen that by opening the door 21 and pulling upon the chain 37', that the downward movement of the disk may be further facilitated and insuring the locking engagement between the extensions 34 and spring lugs 33 although it is to be further noted that the ballast disks 29 are made of considerable weight for affording a material ballast to the boat and are in themselves adapted to automatically assume a locked operative position upon a release of the stern supporting chain 37.

The floats 27 impart stability and insure sea-worthiness to the boat while the ballast disks may be positioned in their inoperative horizontal positions under ordinary conditions but in rough water and when desired to prevent the boat from rocking in rough seas, the ballast disks are operatively positioned extending beneath the keel, and thus affording more efficient ballasting as well as supplying a form of center board for the boat.

While the forms of the invention herein shown and described are what are believed to be preferable embodiments thereof, it is nevertheless to be understood that various forms and modifications may be resorted to which fall within the spirit and scope of the invention as claimed.

What I claim as new is:—

1. A life boat comprising a hull provided with clamp supporting strips oppositely-positioned exteriorly thereof and having circular brackets adjacent the gunwales of the boat, floating buoys mounted within said brackets and extending longitudinally of the boat, bottom extension portions spaced apart upon the bottoms of said strips, and ballast disks hinged between said spaced strip portions beneath the keel of the boat.

2. A device of the class described comprising a boat hull, oppositely-positioned float supporting clamping strips arranged in pairs and substantially surrounding the hull, each pair of clamping strips provided with spaced downwardly-extending ends beneath the keel portion of the hull, spacing blocks between said strip ends, opposite stop lugs and relatively rearwardly-positioned inwardly-projecting spring lugs struck out of said strip ends, pivot pins secured between said pairs of ends below said lugs, weighted ballast disks having integral projecting handles journaled upon said pins and extending between said spaced strip ends and provided with terminal extensions adapted for springing engagement past said spring lugs and in seating contact with said stop lugs.

3. A device of the class described comprising a boat hull, oppositely-positioned float supporting clamping strips arranged in pairs and substantially surrounding the hull, each pair of clamping strips provided with spaced downwardly-extending ends beneath the keel portion of the hull, spacing blocks between said strip ends, opposite stop lugs and relatively rearwardly-positioned inwardly-projecting spring lugs struck out of said strip ends, pivot pins secured between said pairs of ends below said lugs, weighted ballast disks having integral projecting handles journaled upon said pins and extending between said spaced strip ends and provided with terminal extensions adapted for springing engagement past said spring lugs and in seating contact with said stop lugs, pins centrally-positioned through said disks, a link having its ends pivoted to said disk pins and adapted for connecting said disks together for simultaneous movement, a separate chain secured to each of said disks and extending in opposite directions, and an engaging means for the free ends of said chains positioned at opposite ends of the boat and adjacent the deck thereof.

4. A life boat comprising a hull, spring-motor operated propellers carried by said hull, hinged skylight frames upon the deck of said hull, ventilating screens carried by said frames, a pilot house forwardly-positioned upon the deck, a forward and a rear trap door spring-hinged to the deck, and shiftable ballast operating means positioned in close proximity to each of said doors.

In testimony whereof I affix my signature in presence of two witnesses.

JOZSEF KASSA.
